UNITED STATES PATENT OFFICE.

WALDEMAR DYRSSEN, OF NEW YORK, N. Y.

METHOD OF OPERATING ELECTRIC FURNACES.

Application filed March 30, 1922. Serial No. 548,057.

To all whom it may concern:

Be it known that I, WALDEMAR DYRSSEN, a citizen of the United States, and resident of the city, county, and State of New York, have invented certain new and useful Improvements in Methods of Operating Electric Furnaces, of which the following is a specification.

This invention relates to a method of supplying electrical energy to metallurgical furnaces to control the power input to suit the operating conditions during the melting down and the finishing periods.

In the usual practice, where the electric power is furnished to the furnace by means of a transformer, the power input is varied by changing the flow of current in the electrodes by varying the length (that is, the resistance) of the arc a small amount at a fixed transformer voltage ratio or at a fixed transformer connection. The varying of the current has however the effect that the E. M. F. or voltage of the arc itself is lowered at increased current due to the following causes:

First: Resistance voltage drop in the circuit including transformer, busbars, cables, electrode holders, electrodes and in the bath. This loss is proportional to the current, but may increase at a somewhat higher rate than the current due to increased temperature of the copper conductors at higher currents which increases their resistance.

Second: Lower power factor at increased current. The power factor is dependent upon the total reactive resistance of the installation, that is, the reactive resistance of the complete low tension or furnace circuit, including the busbars, cables, electrodes and the bath, the reactive resistance of the transformer proper and the reactive resistance of any additional reactance that may be added in the high tension circuit of the transformer. The total reactive resistance causes a reactive voltage drop which is proportional to the respective currents passing through the respective reactance. This reactive voltage drop can be expressed as a percentage of the imposed voltage. There is a fixed relation between the percentage of

reactance and the power factor according to the following formula:

$$P = \sqrt{100^2 - R^2}$$

wherein P is the power factor and R the reactance in percent. From this formula it can be seen that the power factor is lowered at increased reactance (that is increased current) at lower currents slowly but at higher currents more rapidly. For instance, at

	Per cent.
20% reactance the power factor is	98
40% reactance the power factor is	91.6
60% reactance the power factor is	80

Third: Resistance and reactance in the high tension power supply line and the source of power to the furnace installation. This cause of lower arc voltage at increased currents is usually relatively small but in some cases it might be considerable.

The usual practice, as described above, is sometimes deviated from by using a different transformer voltage ratio or at a different transformer connection during the melting down period and the finishing period, which gives a considerably higher arc voltage during the melting down period than during the finishing period. The higher arc voltage is objectionable from several points of view, such as destruction of the walls and roof of the furnace and damage to the metal in physical and chemical ways.

The initial stage of treating metal in electric furnaces includes a period of melting down the scrap when the maximum of power is used in order to shorten this period as much as possible. After the charge becomes molten, less power is necessary. However, during the refining period it sometimes is desirable to use high power, for instance when new slags are to be melted or when cold metallic additions are made or when the bath has to be heated up rapidly for some cause or another. In treating a molten metal charge in the electric furnace it is often desirable to use a great amount of power during certain other periods to meet various conditions.

By my method I propose to use a constant E. M. F. at the arcs at any input of power

that I desire to employ. I propose to vary the power input by varying the current or amperage, and at the same time employ a novel method of supplying the power in such a way that the arc voltage itself remains constant or nearly constant at either increased or decreased power input. This enables me to increase the power in the arc in direct proportion to the current and this prevents the falling off of power input in the proportional relation (or in extreme cases in actual amount) at increased current as is the case in the usual operation of electric furnaces. I do not employ a long destructive arc or a high arc voltage as is now the case in some other methods of operation.

To enable those skilled in the art to clearly visualize the operation of my improved method, I have prepared the accompanying drawings in which Fig. 1 shows a furnace and the circuits for controlling the power input, the electrodes being connected in star to a three-phase transformer;

Fig. 2 is a similar view showing the electrodes connecting in delta to a three-phase transformer;

Fig. 3 is a diagram showing graphically the theoretical relationships of resistance and reactance, transformer voltages etc., to maintain a constant arc voltage at different loads;

Fig. 4 is a diagram illustrating an extreme case in which the transformer voltage is kept constant and wherein by means of variable reactance, the arc voltage is kept constant at all loads;

Fig. 5 is a diagram similar to Fig. 3 but showing the voltage and other values varied in steps;

Fig. 6 represents diagrammatically the different electrical characteristics in a furnace installation from the time the cold scrap is melted down until the finished or refined metal is poured. The values shown in this figure are based on the characteristics shown in Fig. 5;

Fig. 7 is a diagram showing a case where in a higher arc voltage is constantly maintained;

Fig. 8 shows diagrammatically a furnace and the circuits for controlling the power input as indicated graphically in Figs. 5 and 6.

Referring first to Fig. 1, three-phase current is supplied to the primary windings 10, 12 and 14 which are connected to feed wires 16, 18 and 20 leading to a suitable three-phase alternator, not shown. The primary windings of the transformer excite the secondary windings 22, 24 and 26 which are connected in star with the electrodes 28, 30 and 32 of the furnace 34. This is a typical circuit arrangement and a certain E. M. F. has to be used in order to strike arcs be-

tween the tips 40, 42 and 44 of the electrodes and the charge 50 in the furnace. The voltage between the tip of an electrode and the bath is herein called the arc voltage and referred to by the symbol V_a .

The arrangement shown in Fig. 2 is similar except that the electrodes are connected to the coils 22', 24' and 26' in delta and consequently the arc voltage is equal to the difference in potential between the tips of any two of the electrodes divided by $\sqrt{3}$. Signifying the voltage between the tips of the electrodes in this case by V_e , it follows

$$V_a = \frac{V_e}{\sqrt{3}} \text{ or } V_e = V_a \sqrt{3} \quad 80$$

The actual energy or watts produced at the arc in each case equals the product of the arc voltage and the current strength or amperage.

In the electric arc furnace as ordinarily used current is supplied to the electrodes and a certain voltage must be used in order to produce arcs between the tips of the electrodes and the charge in the furnace. The power produced in each arc is equal to the product of the arc voltage and the current strength or amperage. The power factor in the actual arc is always practically 100%.

According to my improved method, I maintain the arc voltage constant during all periods of operation and at any input of power or current.

At increasing amperages the power factor drops and the voltage loss in the leads increases and in order to maintain a constant E. M. F. at the arc I increase the transformer voltage. This enables me to increase the k. w. input in the arcs in direct proportion to the amperage.

Fig. 3 illustrates graphically the electrical conditions in an installation operating according to my method when using a furnace of the Heroult type of about six tons capacity.

When initially melting down the charge I use a current of about 8600 amperes and maintain an E. M. F. at the arc of 45 volts. At this amperage I use a transformer E. M. F. of about 63 volts when the transformer is connected in star, or a transformer phase voltage of about 109 when connected in delta. After the initial melting down period the charge in the furnace is in a molten state and less power is required to carry on the refining operation. During this stage I reduce the current to approximately 4000 amperes. And in order to maintain the arc voltage constant at this current strength it is necessary to reduce the transformer E. M. F. to about 51 volts between the phase and neutral, or to a phase voltage of about 88.

These theoretical transformer voltages for obtaining constant arc voltage are graphi-

cally indicated by the curve Vt in Fig. 3. The arc voltage is represented by the straight line Va which shows a constant E. M. F. at all amperages. The curves Vr and Vl represent respectively the reactive voltages per lead and the resistance loss in volts per lead. The curve Vdt represents the delta transformer voltages. The line $K. W. A.$ represents the k. w. input in three arcs, the curve $P. F.$ refers to the power factor and the curve Rp , shows the percentage of reactance at different loads.

From the diagram it will be seen that the resistance loss per lead and the reactive voltage per lead is assumed to increase at a constant rate as the amperage is increased. The reactance reduces the power factor at increasing amperages and in order to maintain the arc voltage constant while the power factor decreases, the transformer voltage must vary as shown by the curve Vt if the transformers are connected in star. Or if the electrodes are connected in delta I use the transformer voltages shown by the curve Vdt which are 1.73 times the star transformer voltages.

In the curves as drawn in Fig. 3, I have assumed that all the reactance is located in the low tension circuit, in which case the reactive voltage Vr , is represented by a straight line. If, however, part of the reactance is located on the high tension side of the transformer, either in the transformer itself, or as additional reactance coil, Vr takes the shape of a curve, as indicated by a dotted line Vr' , because the reactive voltage set up in the high tension reactance is proportional to the high tension current, which increases at a faster rate than the low tension circuit. If, therefore, the high tension reactive voltage is by calculation, transferred and added to the low tension reactive voltage, the total reactive voltage will increase somewhat faster than the low tension electrode current.

The result thereof, is that the curves Rp , PF , Vt and Vdt will be modified as shown by the dotted lines Rp' , PF' , Vt' and Vdt' .

In the above it has been assumed that the total reactance is constant or unchanged at all loads. The reactance especially the additional reactance, in the high tension line, can easily be changed or cut in and out at will, in which case the curve Vr can be made to take any shape whatever, at the same time influencing the other curves. An extreme case is shown in Fig. 4, where the transformer voltage is kept constant and by means of variable reactance, the arc voltage is kept constant at all loads. In practice, this method of operation would be practical only within certain limits because it necessitates a very high amount of reactance coils at a low amperage, which, when the amperage is reduced towards zero, must be in-

creased to infinity. The two methods as shown in Figs. 3 and 4 can be combined in any proportion desired to suit the size and the kind of furnace and according to the metal to be melted or treated. In Figs. 3 and 4, an arc voltage of 45 is indicated but the arc voltage can be kept at any desired value within reason by employing the same methods.

My method of operation is not limited to a three-phase, three-electrode, or three-arc furnace, but would apply as well to any electric arc furnace. The arcs can be formed independent of the bath, or between the electrodes and the bath, and the method of operation can be applied to any type of electric arc furnace, regardless of the number of electrodes and kind of current employed.

In practice it is usually not convenient to arrange the electrical apparatus so that the transformer voltage, as shown in Fig. 3, curve Vt and Vdt , or the reactance curves, as shown in Fig. 4, Vr and Rp , are smooth or vary continuously with the current. It is usually necessary to make the necessary variations in steps, which does not give an absolutely constant arc voltage, but which however does not materially change the arc voltage.

In Fig. 5 is illustrated this method of operation. It represents my method as applied to a three-phase Heroult furnace of approximately six tons capacity, two voltages are used and one extra additional reactance. At currents between about 6400 and 8600 amperes, a transformer voltage of 119 delta and 69 star is used and the extra reactance is not connected in the circuit. The power factor varies between 88 and 94 and the arc voltage between 52 and 58. At currents between about 4500 and 6400 amperes, the extra reactance is connected into the circuit at the same transformer voltage. In this case the arc voltage varies between about 52 and 58. For currents lower than about 4500 amperes a lower transformer voltage is used, that is, about 97 delta and 56 star and the arc voltage varies between 50 and 56.

At the start of melting a heat of cold steel or iron scrap there is however an additional reactance in the circuit due to the steel or scrap. This reactance gradually diminishes as the temperature of the charge increases and entirely disappears when the whole charge becomes red hot and non-magnetic. I have estimated that this additional reactance causes a reactive voltage drop of 20 to 30 volts at about 8600 amperes per electrode. Assuming the reactive voltage to be 23, the total reactive voltage is indicated at point Vr^2 in Fig. 5. The value of the corresponding transformer voltages, power factor, per cent reactance, arc voltage

and power in arcs are indicated at Vt^2 , Vdt^2 , Pf^2 , Rp^2 , Va^2 and KW^2 . In this case it is, therefore, necessary to employ a transformer voltage of 82 star or 142 delta as indicated

5 at Vt^2 and Vdt^2 in order to obtain an arc voltage of 52 and a total power in the arcs of 1340 kw. as indicated at KW^2 .

In Fig. 6 is represented the variations in the electrical values during a heat made 10 from cold scrap in a basic electric furnace of which the characteristics are given in Fig. 5. In this figure the horizontal row of numbers from 0 to 210 represents ten minute intervals and the diagram shows the 15 conditions at all periods of operation from the time the cold charge is initially melted until the finished product is poured. The highest transformer voltage 142 (Vdt) without the reactance, is used at the start. 20 After the first three minutes, which are required in establishing steady arcs, the current is kept at the maximum strength or at 8600 amperes per electrode as closely as possible as indicated by the curve A. Due 25 to the reactance in the charge the power factor is low, but it gradually increases as more and more of the scrap around the electrode becomes red hot and non-magnetic. The arc voltage and power increase 30 also. After about twenty minutes, when the greater part of the charge reactance has disappeared, the medium voltage or 119 is used without the reactance. At about thirty-five minutes the effect of the charge 35 reactance has entirely disappeared and the furnace operates at a steady load. At eighty minutes much of the scrap is melted in the center and around the electrode, the furnace becomes hotter and it is necessary 40 to reduce the power gradually by reducing the current. At one hundred and ten minutes the charge is nearly melted and the power is reduced considerably by reducing the current and connecting the reactance in 45 the circuit which maintains the arc voltage nearly constant. After a few more reductions of current the charge and the slag are completely melted and at one hundred and thirty-five minutes the power is shut 50 off and the first refining slag is removed. At one hundred and forty-five minutes the slag materials for the second slag are added and a great amount of power must be used in order to quickly melt the slag and heat 55 the steel which is still comparatively cold. Medium voltage without the reactance is used. At one hundred and sixty minutes the slag is melted up and the power reduced by reducing the current and using the low voltage 60 connection, which maintains the arc voltage nearly constant. Between one hundred and sixty and two hundred minutes the metal is refined at low power. Before tapping or pouring the charge it is in this 65 particular case desired to heat the bath to

a higher temperature and the medium transformer voltage with the reactance is therefore used during the last ten minutes before tap.

If a heat was to be made from non-magnetic materials such as manganese steel scrap, nickel or Monel metal, high voltage with the reactance in the circuit is used during the first twenty minutes, making the conditions about the same as when operating 75 without the reactance in melting ordinary steel scrap

In the acid electric melting process it is desirable to use a higher arc voltage than in the basic process. The electrical characteristics of the same furnace shown in Fig. 5 are represented in Fig. 7 except that the furnace is operated "acid". An arc voltage of about 75 is desired. The extra reactance is in this case connected in the circuit 80 during the whole heat. At start or at a current of about 8600 amperes per electrode a transformer voltage of about 97 star or 168 delta is used, giving an arc voltage of about 73. At lower than 6000 amperes a transformer voltage of about 82 star or 142 delta is used giving an arc voltage of about 69 to 90 depending upon the amount of current used.

Fig. 8 is a diagram showing circuit connections and a furnace arranged to be operated according to Figs. 5 and 6 hereinbefore discussed.

In Fig. 8, 51 is the furnace containing the metal 50 and provided with three electrodes 100 52 each forming arcs 53 between their lower ends and the bath. The electrodes are connected in delta to the low tension coils 54 of a three-phase transformer. The high tension coils are 55, each of which have four connections 56, 57, 58 and 59 leading therefrom. Leads 56 are connected to an oil switch 60, leads 57 to oil switch 61 and leads 58 to oil switch 62. Leads 59 are connected to the three-phases of the power supply which also 105 are connected to the other poles of the oil switches 60, 61 and 62 in such a way that when switch 60 is closed all of the coils 55 are in the circuit and low voltage is obtained between the low tension transformer terminals. When switch 61 is closed a medium voltage is obtained and when switch 62 is closed a high voltage is obtained. The power lines 63 are each connected at one end to a reactance coil 64 and also to an 110 oil switch 65 as shown. The other poles of the oil switch 65 are connected to main power supply lines 66 which also are connected to the other terminals of the reactance coils 64. When switch 65 is closed the 115 reactance coils are by-passed by the current and when it is opened the reactance coils are connected in the circuit. The reactance can then be connected into the circuit independent of the oil switches 60, 61 and 62. 120

and high, medium and low voltages with or without the reactance can be obtained at the low tension transformer terminals.

It will be seen that by utilizing the 6 method described I can maintain a constant or nearly constant arc voltage at different loads for any kind or size of electric arc furnace and that by said method it is possible to 10 vary the power input in the arcs without varying or materially varying said arc voltage. This enables me to obtain a great power input during the melting down period or whenever high power is desired at the same arc voltage or at the arc voltage that 15 is most suitable to use during the refining or finishing periods or when a lower power input is desired.

While I have described my method by quoting specific current strengths and E. 20 M. F., it is to be understood that these examples are to be construed in an illustrative rather than in a limiting sense.

What I claim is:

1. The method of operating an electric 25 arc furnace which consists in maintaining a substantially or approximately constant E. M. F. at the arc regardless of variations in the transformer voltage and varying the amperage to control the magnitude of the 30 power input.

2. The method of melting and refining metal in an electric arc furnace which consists in supplying current of high amperage during the melting down period and supplying 35 a current of comparatively lower amperage during the refining period and maintaining the arc voltage substantially or approximately constant during both periods regardless of variations in the transformer 40 voltage.

3. The method of operating an electric arc furnace which consists in maintaining a substantially or approximately constant E. M. F. at the arc at varying amperages and loads 45 by changing the transformer E. M. F. to compensate for losses due to resistance in the conductors and the drop in E. M. F. due to the lower power factor at increasing amperages.

50 4. The method of operating an electric arc furnace which consists in increasing the transformer voltage in steps at increasing amperages to compensate for drop in E. M. F. due to resistance and reactance and maintaining the arc voltage substantially or approximately constant at all loads.

55 5. The method of operating an electric arc furnace which consists in maintaining a substantially or approximately constant E. M. F. at the arc at varying amperages and loads by decreasing reactance at increasing loads and varying the power factor to compensate for losses in E. M. F. due to resistance and reactance.

60 6. The method of operating an electric

arc furnace which consists in decreasing the reactance in steps at increasing amperages to compensate for drop in E. M. F. due to resistance and reactance and maintaining the arc voltage substantially or approximately constant at all loads. 70

7. The method of operating an electric arc furnace which consists in maintaining a substantially or approximately constant E. M. F. at the arc at varying amperages and loads by changing the transformer E. M. F. and by changing the reactance of the installation to compensate for losses due to resistance and reactance. 75

8. The method of operating an electric arc furnace which consists in increasing the transformer voltage in steps and decreasing the reactance in steps at increasing amperages to compensate for drop in E. M. F. due to resistance and reactance and maintaining the arc voltage substantially or approximately constant at all loads. 80

9. The method of melting and refining metal in an electric arc furnace which consists in supplying a current of maximum amperages and at a higher E. M. F. at the transformer during the melting down period and a current of approximately one-half of said maximum amperage and of a lower voltage at the transformer during the refining period and maintaining substantially or approximately the same E. M. F. at the arc during these periods. 85

10. The method of melting and refining metal in an electric arc furnace which consists in supplying a current of maximum amperages and at a lower reactive resistance during the melting down period and a current of approximately one-half of said maximum amperage and at a higher reactive resistance during the refining period and maintaining substantially or approximately the same E. M. F. at the arc during these periods. 90

11. The method of melting and refining metal in an electric arc furnace which consists in supplying a current of maximum amperage at a higher transformer voltage and at a lower reactive resistance during the melting down period and supplying a current of considerably lower amperage at a lower transformer voltage and a higher reactive resistance during the refining period and maintaining substantially or approximately the same E. M. F. at the arc during all periods. 95

12. In the melting or treating of steel in an electric arc furnace, the method which consists in maintaining a substantially or approximately constant E. M. F. at the arc regardless of variations in the transformer voltage and varying the amperage to control the magnitude of the power input. 100

13. In the melting or treating of steel in an electric arc furnace, in which an arc is 105

struck between an electrode and the charge, the method which consists in maintaining a substantially or approximately constant E. M. F. at the arc and varying the transformer voltage and the amperage to control the magnitude of the power input.

14. In the melting or treating of steel in an electric arc furnace, the method which

consists in maintaining an E. M. F. at the arc which varies approximately 15 per cent above or below a mean constant and varying the amperage to control the magnitude of the power input.

In witness whereof, I have hereunto signed my name.

WALDEMAR DYRSSEN.
